UNITED STATES PATENT OFFICE.

WILLIAM D. CHAMBERLAND, OF MINNEAPOLIS, MINNESOTA, ASSIGNOR OF ONE-HALF
TO THEODORE J. PAGEL, OF MINNEAPOLIS, MINNESOTA.

CONNECTING-ROD JIG.

1,271,018.

Specification of Letters Patent.

Patented July 2, 1918.

Application filed June 11, 1917. Serial No. 174,111.

To all whom it may concern:

Be it known that I, WILLIAM D. CHAMBERLAND, a citizen of the United States, residing at Minneapolis, in the county of 5 Hennepin and State of Minnesota, have invented certain new and useful Improvements in Connecting-Rod Jigs; and I do hereby declare the following to be a full, clear, and exact description of the invention, such as will enable others skilled in 10 the art to which it appertains to make and use the same.

My invention has for its object to provide an improved jig for use in truing up 15 and alining the bearings of connecting rods such as used in explosive engines, for example, and to the above ends, generally stated, the invention consists of the novel construction and combination of parts here- 20 inafter described and defined in the claims. The invention is illustrated in the accompanying drawings, wherein like characters indicate like parts throughout the several views.

25 Referring to the drawings:

Figure 1 is a plan view showing the improved jig and illustrating the manner in which it is used;

Fig. 2 is a side elevation of the same; and 30 Fig. 3 is a front elevation of the parts shown in Figs. 1 and 2, some parts being broken away.

The jig comprises a base 4, preferably cast and lightened up by a central opening. 35 To the rear portion of the base 4, relatively long or high upright gage posts 5 are rigidly secured, and to the front portion of said base, relatively short gage posts 6 are rigidly secured. The said posts 5 and 40 6 preferably have the same lateral spacing. Cast integral with, or otherwise rigidly secured to the rear portion of the base 4, between the posts 5, but nearer to one than to the other, is a heavy lug 8 having a horizontally projected stud 9. The axis of this 45 stud 9 is preferably but slightly above the horizontal plane of the upper ends of the short gage posts 6, and as an important feature, the axis of said stud 9 is located 50 slightly forward of the relatively high rear posts 5 (see particularly Fig. 2). Located between the short front gage posts 6 is a pair of upright laterally spaced alining

pins 10. A point midway between the alining pins 10 is also midway between the gage 55 posts 6.

A connecting rod such as used in explosive engines is indicated as an entirety by the character A, the same having at one end a divided bearing sleeve b, and having 60 at its other end a divided bearing sleeve c. The sections of the bearing sleeve b are connected in the customary way by nut-equipped bolts b¹, while the sections of the bearing sleeve c are connected by machine 65 screws c¹. The particular form of the connecting rod, of course, does not constitute a feature of the present invention. Character d indicates a gage rod which is adapted to be clamped at its central portion between 70 the sections of the split sleeve c.

In the use of the jig either after or before the gage rod d is clamped in the sleeve c, the larger sleeve b may be applied on the stud 9 by lateral movement and adjusted so 75 that it will snugly, but not too tightly, fit the said stud. This being done, the connecting rod will be turned down to a horizontal position while one end of the sleeve b is against the lug 8, and if the sleeve c 80 then fits between the alining pins 10, this fact will show that the two sleeves b and c are in proper longitudinal alinement. Otherwise stated, if one of the said sleeves is offset laterally out of longitudinal alinement with the other, then the sleeve c will 85 not freely enter between the alining pins 10 and the connecting rod must then be bent until the said sleeves will thus aline.

If when the connecting rod is turned 90 down, as stated, the ends of the gage rod d rest upon the upper ends of both short posts 6, then this fact will indicate that the axes of the two sleeves b and c are in the same plane, but it does not indicate, however, 95 that the said axes are parallel to each other. Obviously, if the gage rod d does not rest upon the upper ends of both of the short gage posts 6, then the connecting rod must be twisted, which may be done by using the 100 gage rod d as a lever, until the said gage rod will rest upon both of the said posts 6.

Next, if when the connecting rod is turned into an upright position indicated by dotted lines in Fig. 2, the ends of the gage rod d 105 engage the upper ends of both of the long

gage posts 5, then this fact will indicate that the axes of the two bearing sleeves *b* and *c* are parallel to each other in the said common plane. If this engagement with the 5 ends of the gage rod *d* with the gage post 5 does not take place in the first trial, then the connecting rod must be bent until the above noted contact does take place.

Here it will be noted that by virtue of the 10 forward location of the axis of the stud 9 and the length of the gage posts 5 in respect to the connecting rod, the said connecting rod when turned to the upward limit, shown by dotted lines in Fig. 2, will be stopped by 15 engagement of the ends of the gage rod *d* with the upper ends of the gage posts 5, over which they cannot pass.

By the use of the above described jig, 20 connecting rods may be very quickly and 25 easily trued up and bent into correct form. The fact that the stud 9 is supported at one end only makes it possible, by lateral movements of the connecting rod, to quickly apply the same to the said stud and to quickly re- 30 move the same therefrom. Also the jig is of simple form and may be constructed at comparatively small cost.

What I claim is:

1. A jig for use in truing connecting rods 30 and the like, comprising a gage rod, a base having a raised stud supported at one end only, and laterally spaced pairs of relatively long rear and relatively short front gage posts for engagement with the gage rod held 35 in the common bearing sleeve of a connecting rod having its other bearing sleeve applied on said stud.

2. A jig for use in truing connecting rods 40 and the like, comprising a gage rod, a base having a raised stud supported at one end only, laterally spaced pairs of relatively long rear and relatively short front gage posts for engagement with the gage rod held 45 in the common bearing sleeve of a connecting rod having its other bearing sleeve applied on said stud, and laterally spaced alin-

ing pins secured on said base between said short front gage posts.

3. A jig for use in truing connecting rods and the like, comprising a base having laterally spaced pairs of relatively long rear gage posts and relatively short front gage posts, and provided with a raised bearing lug between said rear gage posts, and a stud secured to and projecting laterally from said lug. 55

4. A jig for use in truing connecting rods and the like, comprising a base having laterally spaced pairs of relatively long rear gage posts and relatively short front gage 60 posts, and provided with a raised bearing lug between said rear gage posts, and a stud secured to and projecting laterally from said lug, said base between said short front gage posts having a pair of upright alining pins. 65

5. A jig for use in truing connecting rods and the like, comprising a gage rod, a base having a raised stud supported at one end only, and laterally spaced pairs of relatively long rear and relatively short front gage 70 posts for engagement with the gage rod held in the common bearing sleeve of a connecting rod having its other bearing sleeve applied on said stud, the axis of said stud being forward of said rear gage posts. 75

6. A jig for use in truing connecting rods and the like, comprising a base having laterally spaced pairs of relatively long rear gage posts and relatively short front gage posts, and provided with a raised bearing 80 lug between said rear gage posts, and a stud secured to and projecting laterally from said lug, said base between said short front gage posts having a pair of upright alining pins, the axis of said stud being forward of 85 said relatively long rear gage posts.

In testimony whereof I affix my signature in presence of two witnesses.

WILLIAM D. CHAMBERLAND.
